UNITED STATES PATENT OFFICE.

GEORGE ELLIOT PERRY, OF CHICAGO, ILLINOIS.

APPARATUS FOR FACILITATING BACTERIOLOGICAL PROPAGATION.

Application filed November 3, 1915. Serial No. 60,324.

To all whom it may concern:

Be it known that I, GEORGE ELLIOT PERRY, a citizen of the United States, residing at Chicago, in the county of Cook and State of Illinois, have invented certain new and useful Improvements in Apparatus for Facilitating Bacteriological Propagation, of which the following is a specification.

This invention relates to apparatus for facilitating bacteriological propagation.

It will be explained as applied to the purification of sewage, although it may be utilized in other fields.

One of the objects of my invention is to provide improved apparatus for encouraging the reproduction and propagation of aerobic biological organisms.

Another object is to provide improved apparatus for providing an adequate and sustained supply of dissolved oxygen for the rapid and healthy growth and propagation of aerobic bacteria.

Another object is to provide apparatus for prolonging the contact of oxygen bearing fluids with the culture medium.

Another object is to provide apparatus whereby the supply of oxygen is made more dependable.

Another object is to provide apparatus which may be readily relieved of the excess growth of biological organisms, their life products and admixed culture media.

Another object is to provide improved apparatus for the continuous biological treatment of organic matter.

Another object is to provide apparatus which will not readily become clogged or choked and inefficient through the growth and collection of the organisms and precipitated matter.

Another object is to provide improved apparatus especially adapted for the purification of sewage.

Other objects and advantages will herein-after appear.

As applied, for example, to the treatment of that culture medium known as sewage, the invention contemplates the continuous passage of the fluid sewage through an aerobic bacteria propagating receptacle or receptacles, wherein means are provided for insuring a continuous abundant supply of soluble oxygen in prolonged contact with

the sewage stream. Preliminary treatment such as the ordinary processes of screening, grit removal, chemical admixture and sedimentation or precipitation may be employed prior to the bacteriological treatment, if any of these steps are necessary or deemed desirable. The growth and propagation of the bacteria and the formation of the resultant or accompanying "sludge" is carried on upon shelves located in the receptacle and disposed at suitable inclinations to insure the proper avalanching of the collecting matter so that the maintenance of the system at a desired degree of efficiency is insured.

Attempts have been made to successfully aerate fluids bearing organic matter undergoing biological treatment, by bubbling air therethrough. More complete dispersion of air through the treated fluid has been attempted by employing beds of stone, etc., through which the air and fluid is caused to flow. Such expedients are objectionable because the time the air is in contact with the fluid is relatively short, reducing the time available for oxygen solution. Also when the source of fresh air is, for any reason, interrupted the supply of oxygen available for solution is exhausted practically instantaneously. The use of stone or other porous dispersion beds are further objectionable in that the "sludge" accumulates upon and among the stones and they must be cleaned in order to maintain the system at a high or constant degree of efficiency. Such cleaning is expensive, tedious and unpleasant.

Pursuant to my invention the stream of organic matter laden fluid has a stream of treating fluid, for example air, conveyed in a tortuous path therethrough and in contact therewith. The air is substantially confined to a definite, predetermined tortuous path which prolongs its contact with the treated or solvent fluid. The air path is so constituted that, in case of interruption of the source of supply, there is still a considerable quantity of air trapped or retained within the solvent fluid.

The sloping shelves, upon which the desired aerobic bacteria propagate and whereon "sludge" is deposited cleanse themselves of surplus accumulations. The sludge

gathers until the weight of the accumulation overcomes the adhesion between particles, whereupon quantities will slough off or avalanche and settle to lower levels and finally reach the bottom of the receptacle where it may be removed readily. Thus the aerated propagating grounds are self cleansing to the extent that they will not clog and foul because of excess accumulations of "sludge."

10 The accompanying drawings illustrate how the invention may be advantageously employed in the purification of sewage.

The views in the drawings are as follows:

Fig. 1 is a central vertical section through 15 a sewage treating system.

Fig. 2 is a top plan thereof.

Fig. 3 is an enlarged cross section taken on line 3—3 of Fig. 2.

Fig. 4 is a transverse section taken on line 20 4—4 of Fig. 1.

Fig. 5 is a perspective view of a series of built up air conducting purifying tile.

Fig. 6 is a bottom view of one of the tiles.

Fig. 7 is a section taken thru the structure shown in Fig. 5 where one tile is superposed upon another showing the bottom tile and the one immediately thereabove.

Fig. 8 shows a perspective bottom view of a different form of tile used for the same 30 purpose as those shown in Fig. 5.

Fig. 9 is a plan bottom view of tile shown in Fig. 8.

Fig. 10 is a transverse section shown on line 10—10 of Fig. 3.

35 Fig. 11 is an enlarged section taken on line 11—11 of Fig. 10.

In all the views the same reference characters are employed to indicate similar parts.

40 It may contribute to a better understanding of my process if in describing the apparatus I incidentally refer to the processes that take place in the various receptacles and subsequently describe the entire process 45 more fully.

In the schematic representation of my invention I have illustrated two separate sets, or independent series of tanks, containers or receptacles and in describing them I will 50 place reference characters on one set of series of duplicate receptacles and indicate similar parts in the other set when necessary by similar characters with the additional exponent prime(').

55 A sewage receiving tank 20 is divided into two compartments by a wall 21. The wall does not extend to the bottom of the tank 20, as shown more clearly in Fig. 4, but extends in an angular direction towards 60 the intermediate dividing wall 22 forming a hopper like receptacle 23. 24 is the receiving receptacle into which the sewage is primarily admitted thru a conduit 25. In the receptacle 24 are a series of inclined 65 screens 26, 27 and 28, consisting preferably

of parallel bars or rods spaced apart to permit the liquid and the finer parts of sewage freely to pass therethru and adapted to catch coarser débris that may float upon or near the top surface thereof, or which 70 may be contained within the body part of the incoming, more or less fluid material.

The bars of the screen 26 are further apart than are the bars of screen 27 and in like manner those of the screen 27 are 75 further apart than are those of the screen 28, so that much of the material that is not caught by the screen 26 will be caught by the screen 27, and the most of that which is not caught by the screen 27 will be caught 80 by the screen 28. I do not limit myself to this particular screen construction, but may use any efficient type of screen or dispense with them without prejudice to my claims. 85

The receptacle 24 is divided into three 85 screen chambers 29, 30 and 31, separated by the respective screens and having hopper-like bottoms. The screens rest upon the top of the walls dividing the hoppers and are inclined in a direction toward the flow of 90 the confluent. The upper edges of these screens are a few inches below the water line 32 of the screen chamber and rest upon tapered troughs 33, 34 and 35, respectively, which pass thru the partition wall 21, into the sludge chamber 36. Slide valves 38, 39 and 40 are adapted to close the ports thru which the screenings pass so as to entirely 95 separate the screen chambers from the receiving chamber 36. The floating débris being held or restrained by the screens and thus caused to take an upward path will be caught in the troughs and the heavier mineral matter will be deposited in the hopper bottom of the chambers 29, 30 and 100 31. This heavier sediment usually contains very little offensive matter and in the course of time, as it accumulates, may be removed from the screen chambers 29, 30 and 31 by a series of pipes 41. The sewage flows from 105 screen chambers thru a valve port 42, controlled by a valve 43 into a conduit 44. This conduit is divided from the conduit 44 by another valve 45 so that the conduits 44 and 44' may be connected, should occasion require. The water line, or water level 110 in the receptacle 36, is at 46, and is maintained lower than is the water line or level 32 in the screen chambers. In practice there is about six feet difference in the 115 water heads for a purpose to be hereinafter more fully described.

When the sewage flows from the screening chambers into the conduit 44, it passes therefrom into the relatively long narrow 125 flow or purifying chamber 46. The purifying chamber is provided with a bottom formed into a series of sloping walled hoppers 48, and consists of a series of like sections, preferably about eight to twenty 130

or more, depending upon the character and volume of sewage to be purified, of which each section contains a hopper and duplicate apparatus. Therefore, my description 5 will be confined to a single section.

Each section contains a plurality of stacks of tiles 50 and 51, (the purpose and use of

which will be hereafter more fully described) arranged or stacked in the order 10 more clearly shown in Fig. 10, inclined for instance, from the right upwardly toward the left and another series of similar tiles 52 and 53, the same in every respect, with the exception that the tiles 52 and 53 are 15 stacked so as to be inclined in the opposite direction, that is to say, from the left upwardly toward the right. Each of the

stacks referred to is composed of a series 20 of individual tiles 54, made preferably of cement or some other suitable non-absorbent material, having a relatively smooth upper receiving surface of the wall 55 and a series of internal ribs or baffles 56 projecting from the other side of said wall. The ribs 56

25 extend transversely across the under side of the tile from the side wall 57 to the opposite side wall 58. When the tiles are inclined, as shown in Fig. 10, and submerged in the sewage liquid there is contained be-

30 tween the under surface of each of the ribs 56 and the wall 55, an air pocket or path 59. Looking at Fig. 9, it will be observed that there are 12 cross ribs 56 and that the

35 fourth rib from the bottom and the eighth rib from the bottom extend in unbroken continuity from wall 57 to wall 58, but that the other ribs have at their ends, air passages or notches 60, alternate ribs having notches at the same end. This divides

40 the under side of the tile into three sections or air paths, each section terminating in a tuyère, or air passage 61, for escape of the air from the passage 59 to a similar passage in the adjacent superposed tile, as

45 will be hereinafter more fully shown. The side walls 57 and 58 of the tile are provided with laterally projecting lips 62, by means of which the tiles may be supported or suspended from proper support, or one upon

50 the other, as shown in Fig. 10.

It will be readily seen that as the deposits of solid matter upon these wetted sloping surfaces 56 increases and as the zoologic growth increases thereon, there will come a 55 time when the surfaces will become over-loaded and the mass will develop cleavage planes and will thereupon avalanche, slide or slough away from the surfaces 56 delivering a certain more or less compacted mass 60 of sludge therefrom which will deposit upon the surface 55 immediately below, thus freeing the surface 56 for further accumulation.

Projecting inwardly from the wall 57 and intermediate of tuyère 61 are inwardly projecting noses 63 which are of the same width

as the side wall 57 and serve as guides for the air escaping thru a tuyère of the tile immediately below. Made in the side walls 57 and 58 are obliquely positioned semi-circular depressions 64 which with the adjacent tile in the same horizontal plane form a circular opening for an air conducting pipe 68 which passes down between adjacent stacks of tile. Transversely of the hopper 48 in the chamber 47 are bar or beam supports 69 upon which are secured angular supports 70, upon which the first tile, of the stack of tiles, rests, and thereafter each tile affords a support for the adjacent superposed tile. 80

It will be observed that each supporting rib 56 has its upper surface wetted and which is inclined at a predetermined angle so that deposits may accumulate thereon and upon which the organisms desired to be cultivated may live and flourish in their close proximity to the air within the conduits or passageways 59 which constitute the source of oxygen so necessary to the growth, propagation and maintenance of 85 these desirable organisms.

Located below the lowermost inclined tile of the stack is an air distributor of any acceptable or efficient design, as for instance in this embodiment, consisting of baffle 90 plates 72 and 73, joined by a hollow partition 74, thru which the air conducting pipe

68 passes to the bottom thereof. Immediately below the terminal end 68^a of the pipe 68 is an air deflector 75 and immediately above the end of the pipe 68^a is an oblique wall 76 and 76^a that form an air pocket 77 above the end 68^a of the pipe. The baffle plates 72 and 73, are provided with notches thru which the air, coming 100 thru the pipe 68, passes to the underside of the first superposed tile. Looking at

Fig. 10, the air streams that will pass from the pipe 68 thru the notch 69^a is indicated by a series of bubbles 180 which enter between the second and third ribs, near the bottom of the first tile. The air will pass along the longitudinal air passages or conduits 59 between adjacent ribs until it comes to an air opening 60, from whence it will 105

pass into the next air pocket and so on thru each adjacent rib in the opposite direction, until it comes to the tuyère 61. It will then pass from the tuyère as shown at 82, in

Fig. 10, along the nose 63, which guides it 110 into the first air passage of the next superposed tile. This same stream of air will then pass along the adjacent air passages in the same manner, passing thru the air opening 60 at the alternate ends of the 115 rib 56 until it encounters the next tuyère 61 when it will again pass to the next tile

120 immediately thereabove and to the third tile in the series and in like manner will 125 continue to pass from the lower section of 120 130

the tiles to the tile immediately above in proper consecutive order until it reaches the top tile of the stack, from whence it will escape to the outside atmosphere, above the 5 liquid contents.

Another stream of air 83 from the pipe 68 will flow from the opposite side of the baffle plate 73 and pass into air pockets between the fourth and fifth ribs, and in like 10 manner it will pass in alternate directions thru adjacent air pockets and escape upwardly again and be directed by the nose 63 into a section of the tile immediately thereabove. The air stream 84 escaping thru 15 the opening 78 in the baffle plate 72 will pass upwardly thru the liquid until it strikes the last series of longitudinally extending air pockets from whence it will escape thru the last tuyère 61 to the similar pockets of the 20 immediately adjacent superposed tile and thus it will be seen that the air coming thru pipe 68 is provided with a plurality of tortuous paths, thru elongated passageways or 25 pockets beneath consecutive tiles and in which it is detained immediately above a relatively large surface area of the fluid 30 contents, giving the fluid contents ample opportunity and sufficient time within which to absorb the oxygen from the air as it slowly passes thru this elongated path.

Of course it will be understood that the buoyant tendency of the air will cause it to move upwardly thru the passages without 35 artificial means but that slight pressure may be applied to the air coming in the pipe 68 to accelerate this effect and thereby the speed with which the air may move thru this elongated path may be slightly varied 40 by varying the pressure applied to it while in the pipe 68 or the reservoir with which it connects. It will be observed that immediately below each of the air pockets 59 is a 45 relatively smooth inclined receiving surface 55 provided by the tile immediately below so that any precipitation from the passage or the liquid contained therein will be caught by the surface 55.

Precipitated matter sloughed away from the surface 55 will descend to the hopper 48 50 and at appointed times may be removed therefrom thru siphon pipe 80 connected to main 82 by a valve 81. Main 82 is connected to the sludge pump or air operated sludge forcing ram 83 and is also furnished with 55 discharge means delivering by gravity into sludge storage tank 36. Since it will be found that much higher life abounds in these tanks, it is necessary to so order the outflow 60 means as to keep within the tank, crustacea, fish, mollusks, etc. as might attempt to escape or be carried out with the effluent, as it is desirable that such life be retained to aid 65 the process of purification. Therefore, I leave clear at the outlet end of tank a considerable space so that any current set up in

in the flowing sewage may be somewhat stilled and a comparatively slow flow be accomplished for the effluent.

The sludge withdrawn thru siphon pipe 80 and pipe 82 is preferably delivered to the 70 sludge storage tank 36 by means of suitable discharge outlets and as the level 36' of the sludge storage tank is lower than the level 32 which is also the level of the treating tank there will be set up, upon the opening 75 of the proper valves 81, etc. a flow by gravity from the hopper in question to the sludge storage tank. When it is thought that a sufficient quantity of sludge has been delivered from that particular hopper, then 80 valve 81 is closed. The sludge in the sludge storage tank is kept aerated by air retaining tile which constitute a series of tortuous passageways or conduits for the air to traverse 85 on its passage to the surface

Referring to Figs. 4 and 5, 90 represents a unit of these troughs or tile. They are here shown as suspended from above but they may be supported in any suitable manner and they may be made in a single structure, if desired.

The effluent flowing beneath baffle 84 escapes to outfall conduit or sewer 85 by means of weirs or gates 86 and flows away, as merely inoffensive aerated water to the 90 point of outfall or discharge. Should it be desired to sterilize the effluent by chemical means, chlorine gas may be injected into the air supplied to the last few rows of tile and this will thoroughly and effectually sterilize 100 the effluent, or beneath the tile may be placed electrically energized electrodes of iron which will also produce the same effect, the gases escaping from the electrodes being collected by the tile and held until absorbed 105 or replaced by more gases.

The sludge withdrawn thru siphon pipes 80 and 82 is preferably delivered to the sludge storage tank 36 by means of a suitable 110 discharge outlet and as the level 36' of the sludge storage tank is lower than the level 32, the level of the purifying or treating tank, there will be set up, on the opening of the proper valve 81, etc. a flow by gravity 115 from the hopper in question to the sludge storage tank. When it is deemed that sufficient sludge has been delivered from that certain hopper, then valve 81 is closed.

The sludge in the storage tank 36 is also aerated by air retaining tile 90 which constitute a series of tortuous path ways or conduits for the air to traverse on its passage thru the sludge to the surface.

Referring to Figs. 4 and 5, 90 represents a unit of these troughs or tile, as also 125 shown in Figs. 1 and 4, and they are here shown as preferably suspended from above by air pipes and rods but they may be supported in any manner without departing 130 from the spirit of my invention.

As will be seen in Fig. 5 the suspension rods 91 and 91^a are solid, but 92 and 92^a are air conducting pipes. These rods and pipes extend thru all the tile to the bottommost and are suitably headed at the lower ends as for instance by a nut and washer, so that the weight of the tile is upheld by the tensile strength of the pipes and rods.

10 Now referring to Fig. 6 it will be seen that the air conducting tile consists of a trough 93 braced longitudinally by the reinforced rib 94 and divided into compartments 97, 97^a, 97^b, by cross braces 95^a, 95

15 and 95^b, which may be of greater or less number as the tiles are short or long. At either end of ribs 94 is a sleeve or bearing column 96^a and 96^b, thru which the supporting tile rods are passed. At the end

20 compartment 97^b will be seen an opening or tuyère 98 thru which air trapped beneath a trough 93 when augmented by a further supply, may escape to the trough above. Thus in Fig. 7 the streams of air

25 being supplied at the end of 93^a, bubbles under cross ribs 95^a, 95 and then beneath 95^b, entering in turn spaces or compartments 97^a, 97, etc. and lastly 97^b. Thus it escapes thru tuyère 98 and is immediately confined by

30 compartment 97^a in tile 93^b, while in Fig. 5 it is shown that from 93^b the air escapes to 93^c, thence to 93^d, and from that tile it bubbles thru tuyère 98 to 93^e, then to 93^f and will thus

35 traverse the vertical spiral pathway around the unit until it is delivered to the atmosphere from the final exit at the top.

However, had the tile been supported from two rods instead of four as is clearly shown in Fig. 5, the ends *a* and *b* would have alternated above each other and thus the air would have traversed a path and a return path back and forth until it reached the top. Thus it is shown that these tiles or troughs will contain numerous air sur-

40 faces, as shown in Fig. 5, in tile 93^e which is broken away to show the air and water line 98. These surfaces are being constantly agitated by the continued bubbling of the air beneath the partitions 95 which agitation aids greatly the absorption of oxygen from the air exposed. This bubbling agitation is also shown in Fig. 10.

45 While the sludge which is delivered into a tank 36 from the hopper 48 has already been more or less worked over by animalculæ of various genera the action will continue as long as the liquid is aerated and organic matter remains, though I deem it wise at the time of delivering the first sludge from hoppers 48 into tank 36 to agitate the contents, then or at another time, by means of air released thru pipes 99 or by pumps or other means, so that the fresh delivered sludge may be thereby thoroughly mixed and incorporated with

the older and more reduced sludge and thus I avail myself of the greater quantity of organisms existing in the old sludge and which will at once attack and act upon the fresh increments and also receive the benefit of the digestive enzymes and active ferments produced in excess to that required to digest the older sludge. After the period of agitation has ceased or the contents of the tank be thoroughly mixed the tank is allowed to remain quiescent save for the constant circulation of air thru the tile so as to separate by quiescent precipitation the solid from the more liquid parts of the sludge and just before again receiving fresh sludge the supernatant liquid is drawn off thru valves 100 and delivered by pump 83, back thru pipes not shown, to the settling tank, preferably at the fresh or raw sewage end, thus seeding the fresh sewage with micro-organisms and obtaining the benefit of enzymes, active ferments, etc. produced while the sludge is being digested to aid in flocculating the dissolved and suspended matter of the raw sewage. By opening valve 81 and educting—by pump 83—from tank 36, we can thus empty tank 36 of its more or less liquid contents which may be disposed of by compressing in sludge presses; drying the same on sludge beds or by pumping direct to burial beds or trenches.

I prefer to press the sludge in sludge presses, thereafter drying the cakes and de-greasing same by percolation if necessary and after the sludge cakes are dry, to granulate or pulverize same, thus producing a fertilizer which may be used either as produced or mixed with other materials and then used for fertilizing purposes.

Having disclosed the apparatus which I use to obtain the results desired I will briefly refer to my process.

The sewage is received, as for instance, in the chamber 24, and as chamber 24 is of much larger cross section than the incoming stream, a desired drop in velocity is obtained. This for one reason is to allow the inorganic solids, in a large measure to subside thru hopper bottoms or chambers 29, 30 and 31, and as the sewage passes thru the screens 26, 27 and 28, the floating and larger débris is separated therefrom and is either raked into the troughs 33, 34, and 35, or is deposited therein by the action of the current. These screenings are delivered by gravity into the sludge storage tank 36, thru valves 38, 39 and 40, from time to time.

The screened raw sewage is passed from chamber 24, thru passage 43, and enters the transverse gallery or conduit 44 from which it may be discharged into either or both of the purifying chambers 46 of this tank, or may be carried to any other tank of the same installation, or may be by-passed, by

suitable by pass, not shown, direct to the outfall 85. Should it be necessary to add any coagulating chemical to aid this precipitation in the purifying tank this may be done at any point between the conduit 25 and the entrance to the tank 46.

The sewage passing from flume 44 into tank 46 impinges upon the first stack of tile 52 and 50, on the one side which is directed upward and on the other side directed downward, so that in passing thru the tank a continuous vertical repositioning of the liquid takes place in a manner that causes a somewhat spiral path of the sewage thru the tank 46, thus causing all parts of the flow to be treated equally.

As the sewage passes thru the stacks of tile it is separated into a multitude of thin streams or ribbons of sewage by the bodies 20 of the tile bridging from support to support. Above these ribbons or streams is a constantly renewed supply of fresh air and below them is a plate surface covered with an infusorial and bacterial growth and 25 slitted up with an absorbent and attractive mass of activated sludge which is constantly withdrawing organic matter from the flowing stream for the sustenance of this infusorial and other life and it is also giving out 30 continuous streams of coagulating enzymes by reason of the surplus of digestive juices produced while the organic material is being digested by this resident life.

At the same time the downwardly projecting ribs of the tile above aid in producing 35 eddying currents which tend to stir the sewage, mixing that which has absorbed the oxygen from the air streams with the less oxygenated liquid and exposing it all continuously to the infusorial and other life 40 upon the various wetted or submerged surfaces and to the absorptive action of the spongy mass of previously deposited sludge and jelly like colloidal matter upon the shelf 45 like part.

It will be observed that each rib has a plane surface wetted, which rests at a pre-determined angle, so that deposits may accumulate thereon and upon which the organisms desired to be cultivated will live and flourish in their close proximity to the air streams in the conduits or passages 55 which constitute the source of the oxygen so necessary to the growth, propagation and 60 maintenance of these desirable organisms. And it will be readily seen that as the deposits of solid matter, upon these wetted sloping surfaces 56, increase and the zoologic growth also increases therein, there will come 65 a time when these surfaces will become overloaded and the mass will develop cleavage planes and will therefore avalanche, slide or slough from surface 56 delivering a more or less compacted mass of sludge 70 therefrom which will deposit upon the sur-

face 55 immediately below, thus freeing the surface 56 for further accumulation ad infinitum. In the act of discharge of sludge from 56 and the deposit of same upon surface 55 the mass delivered from 56 becomes 70 distributed more or less widely upon the surface 55, thereby exposing its inner substances to an added biological reworking upon surface 55 until at such times as gravitational effect of the mass of material deposited by 75 these means upon surface 55 overcome the natural adhesion of such material to the sloping surface of 55, cleavage planes will thereupon develop and the surplus of the deposit will avalanche toward the bottom 80 of the tank thru the spaces between the piles of tile 50, 51, 52, 53, etc. and in a state much more compact than the same solids were when in the raw sewage upon entry to the tank, and therefore since they are 85 thus more compact the act of traversing the distance between the tile from whence they were discharged and the hopper bottom will consume less time than would have been 90 consumed had such particles been deposited from the sewage in their highly comminuted and separated form at their entry to the tank.

Now, therefore, between the enzymes, 95 gravitational attraction of the tile, the absorptive action of the previous deposited sludge, and the continuous and growing appetite of the bacteria, infusoria, rotifera, vorticella, crustacæ, and worm and larvæl life in general, not to speak of the purifying effect of 100 distomaceous and higher plant life—the colloidal matters in the sewage will be coagulated and withdrawn, the gross suspended matter deposited and the dissolved organic matter precipitated, and these actions with a large amount of oxygen dissolved in the effluent by reason of the air supplied, will 105 give a crystal clear effluent stable and non-putrescible.

Now in more or less polluted water of 110 streams or lakes will be found diatomaceous and higher forms of plant life such as sphæerotilus natans, euglena, leptomitus lac-teus, carchesium, oscillatoriæ, green flagellata, protococcus and other actively motil 115 green cells, which lower green forms can according to high authorities, take their nitrogen and carbon dioxide better from organic sources than from inorganic, and consequently take an important part in the action 120 of purification. It is well known to science that the action of sunlight upon the green or chlorophyll cells of aquatic and other plants, gives these cells the energy necessary 125 to break apart or separate the carbon of carbon dioxide, from the oxygen, and as the carbon is utilized in building up the tissues of the plant, the surplus oxygen is freed and becomes dissolved in the water or diffused in the atmosphere and therefore these 130

chlorophyll bearing plants thru the action of the sunlight will augment the oxygen supply of the water in which they exist. Therefore, I have purposely provided spaces between the stacks of tile so that the sunlight may penetrate into the sewage between these stacks and thus give these chlorophyll bearing plant bodies the means whereby they may break down the carbon dioxide dissolved within the water and deliver to the sewage the oxygen from said carbon dioxide and should it be deemed necessary to cover these tanks with a roof, the roof should be more or less transparent or constructed in a similar manner as in green-houses. Artificial sources of light, having relatively great actinic power may be successfully substituted for sunlight.

When I have placed one of my installations in operation I purposely seed the tanks with cultures of desired organisms by any suitable means, in accordance with the result which I wish to obtain in the precipitated sludge. For instance, utilizing organisms which have a preference to fats as food should we desire to consume the fats which ordinarily would be therein, or the augmenting of the fats to produce more thereof than ordinarily would be produced by those organisms which produce and store oils and fats in their bodies, if it be desired to increase the nitrogen content of the sludge, by seeding with nitrogen fixing organisms, acting in a similar manner to those producing the nodules on legumes, thus controlling the results obtained by varying the predominating organisms operating within the workshop which I have provided and it is to be remembered that any time the free swimming bacteria, infusoria, motil green cells and such life will be as great in number as those which become fixed within said workshop, so that in my invention I have furnished means for the artificial stimulation of the work and propagation of the workers of both fixed and swimming animalcula of various types, crustaceae, worm and larval life and plant life from the lowest to the highest whereby their efforts may be stimulated and controlled to accomplish such end in the reworking of the sludge deposited from the fluid, as I desire.

A battery B, or other source of electric energy may be used, in connection with the plus and minus plates shown to be submerged in the sewage liquid to decompose a portion of said liquid by electrolytic action to there-

by provide a buoyant gas or fluid, such as oxygen or the like, within the liquid instead of introducing such a fluid or gas therein from extraneous sources as described. Any other known means of providing such gas or fluid is within contemplation of my invention.

Having described my invention, what I claim is:

1. Apparatus for promoting the development of organisms, comprising a receptacle for a fluid body in which the organisms develop, and means for trapping and retaining a gas below the surface of the fluid and providing a self cleansing propagating ground for the organisms.

2. Apparatus for promoting the development of organisms, comprising a receptacle for a fluid body in which the organisms develop, and a series of sloping walled open bottomed tiles for confining a gas below the surface of the fluid and in contact therewith, the slope of the walls of the tiles being sufficient to allow gravity avalanching of excess accumulations of sludge.

3. Apparatus for promoting the development of organisms, comprising a receptacle for a fluid body in which the organisms develop, and a series of sloping walled open bottomed tiles providing a definite tortuous submerged passage for passing and trapping a treating gas in contact with the fluid, the slope of the walls of the tiles being sufficient to cause gravity avalanching of excess accumulations of sludge.

4. An apparatus for purification of a liquid bearing putrescible organic matter comprising a structure provided with an inverted channel and inclined surfaces therebelow, submerged in said liquid to receive matter precipitated from the liquid and means for introducing air in said channel.

5. Apparatus for promoting the precipitation of organic matter from fluid bodies, having a receptacle for a fluid body, and means for passing a stream of air through and in contact with the fluid body over a tortuous predetermined confined path submerged within the body, and means for trapping and holding air in the paths.

In testimony whereof I hereunto set my hand in the presence of two subscribing witnesses.

GEORGE ELLIOT PERRY.
